FOLDABLE TRAVERSING SCREEN

James Hirashiki, Los Angeles, Calif., assignor to Universe Products Company, Los Angeles, Calif., a limited partnership

Filed Feb. 5, 1962, Ser. No. 68,642

Term of patent 14 years

(Cl. D54—2)

Fig. 1.

Fig. 3.

Fig. 2.

FIGURE 1 is a perspective view of a foldable traversing screen showing my new design.

FIGURE 2 is a perspective view on a larger scale of one of the repeating individual blocks from which said foldable traversing screen is assembled.

FIGURE 3 is a perspective view of the rear of the block shown in FIGURE 2.

I claim:

The ornamental design for a foldable traversing screen, substantially as shown and described.
